DISPLAY RACKS

Leon H. Best, Galva, Ill., assignor to John H. Best & Sons, Inc., Galva, Ill., a corporation of Illinois
Filed Oct. 18, 1962, Ser. No. 231,471
4 Claims. (Cl. 211—44)

This invention relates to a display rack for supporting rolls of linoleum or other heavy rolled material in an upright fashion.

Rolls of linoleum, carpeting and the like are sometimes more conveniently displayed for customer inspection by disposing the same vertically on end. Such a display is a space saver if nothing else. However, there is danger in an arrangement of this kind, unless the rolls are stabilized or supported, since it is an easy matter for one roll to be tipped over, likely to cause the whole group to fall like tenpins. It will be appreciated that rolls of material of this kind are quite heavy, so the chance of a serious accident, when a roll is upright without support, ought to be taken into account.

The primary object of the present invention is to make available a display rack for stably supporting upright rolls of linoleum or the like against inadvertent tilting, and in particular one that can be inexpensively manufactured and assembled. Specifically, an object of the invention is to construct such a rack inclusive of a plurality of arms supported by individual support elements on a cross member, each such arm having an end adapted to be anchored to the upper end of such a roll and so related to the support element on the cross member that a force tending to upset the roll applies tension to the arm and induces an even more effective connection between the arm and said support element.

Under the present invention, and such constitutes another specific object hereof, linoleum rolls or the like are supported on end against inadvertent tilting by having resort to a horizontal arm anchored to the upper end of the roll. The arm is gripped by a spring clip supported on a cross member, and a connection is afforded between the spring clip and the arm so that tension applied to the arm in a horizontal direction, as by a tilting force applied to the associated roll, induces an even more effective clasp between the spring clip and the arm. Furthermore, the clip resists attempts to move the roll laterally with the arm as a radius. Even so, it is possible, when desired, to swing or tilt the arm vertically about the axis of the cross member to enable the arm to be released purposely with respect to the roll of material.

Other and further objects of the present invention will be apparent from the following description and claims and are illustrated in the accompanying drawings which, by way of illustration, show a preferred embodiment of the present invention and the principle thereof and what is now considered to be the best mode contemplated for applying the principle. Other embodiments of the invention embodying the same or equivalent principles may be made as desired by those skilled in the art without departing from the present invention and the purview of the appended claims.

In the drawings:

FIG. 1 is a perspective view of a group of linoleum rolls standing on end and supported by the rack of the present invention;

FIG. 2 is a top plan view of the assembly shown in FIG. 1, and being broken away;

FIG. 3 is a perspective view of a clip and associated holding arm;

FIG. 4 is a fragmentary plan view on an enlarged scale in comparison to FIG. 1 showing the manner in which the arms project from opposite sides of the cross member;

2

FIG. 5 is a sectional view substantially on the line 5—5 of FIG. 2; and

FIG. 6 is a fragmentary elevation of a portion of the display rack structure.

5 Referring to FIG. 1 of the drawing, a plurality of linoleum rolls R in a display room are set on end in an upright fashion in two parallel rows, and are secured or anchored in this condition by holding devices that are a part of the display rack 10 of the present invention.

10 The rack 10 includes an elongated cross member in the form of a rod 12, and this rod is of such length as to extend substantially from one end extremity of the rows of rolls R to the other end extremity as will be evident in FIGS. 1 and 2.

15 The rod 12 is in an elevated horizontal position somewhat above the upper ends of the rolls R which, incidentally may be of six-foot width, that is, the upper end of each roll R is six feet above floor level. The rod 12 is supported in this position by a pair of upright posts 14 and 15 located at opposite ends of the rod 12.

20 The posts 14 and 15 have the lower ends thereof secured to a pair of floor mounted base plates 16 and 17. The ends of the cross rod 12 are secured to the upper ends of the supports 14 and 15 as by bolts 20 which have 25 the threaded inner ends thereof anchored in a nut plug or equivalent retainer 12N, FIG. 5, arranged within each of the open ends of the tubular cross member 12. It will be appreciated that any suitable means can be used to support and secure the cross member 12 in its elevated position.

25 Each roll R, except for the four end rolls as noted hereinafter, is secured against tipping over by intermediate arms 21 which, as shown in FIG. 2, project outwardly from opposite sides of the cross member 12. By using 30 end arms 22 of slightly different configuration for the four end rolls R, as hereinafter described, it is possible to shroud or conceal the base plates 16 and 17 by the two end rolls at each end of the linoleum roll assembly.

35 The intermediate arms 21 are of identical configuration. Thus, each arm 21 includes a horizontal leg 21A and a downwardly bent leg 21B at one end thereof. The leg 21B, which is of vertical extent, enables the arm 21 to be anchored to the roll by being disposed in the core opening 23 at the upper end of each roll as will be evident in FIGS. 2 and 5.

40 Associated with each arm 21 is a substantially U-shaped spring clip 25 having a bight portion 26 adapted to be saddled on the upper side of the cross member 12. Each clip includes two downwardly divergent legs 27, and these 45 are disposed on opposite sides of the cross rod 12 when the clip is set thereon.

45 The lower ends of the spring legs 27 are provided with 50 apertures 30. These apertures are in registry with one another and are configured to neatly receive the leg 21A of the arm 21. By slightly compressing the legs 27 inward in opposition to the spring force, the apertures become sufficiently aligned to enable the leg 21A of the related arm 21 to be easily projected therethrough, as 55 will be evident in FIG. 3.

60 When the compressive force on the clip legs is released, after positioning the leg 21A of an arm 21 in the openings therein, the spring force of the legs 27 is applied to spaced points at the underside of the arm 21, resisting 65 displacement of the arm 21 relative to the clip, and the parts are configured and designed to produce this result.

65 The underside of the leg 21A of the hold-down arm 21 is notched at 21N as shown in FIGS. 3 and 5. This notch is configured to engage the lower edge defining the aperture 30 in the leg of the related spring clip 25 that is on the near side of the roll R (leg 27A, FIG. 5) supported by the related arm 21. In other words, each arm 21 is,

through its notch 21N, secured to the leg of the related clip that is on the near or adjacent side of the hook end 21B of the related arm 21.

As shown in FIG. 5, each arm 21 secured to a clip 25 can be pivoted freely in a vertical plane about the rod 12 about an axis, and such relationship enables a roll R to be removed from the rack when desired. However, if a force F, FIG. 5, is applied to a roll R that is anchored by an arm 21, tending to tilt or upset the roll relative to its upright position, such produces a forward pull or tension on the arm 21, and a force in turn is exerted on that leg 27A of the related clip 25 which is nearest the roll to which the upsetting force has been applied. Concurrently with this action, the leg 27A of the clip engaged by the notch in the arm 21 tends to be pulled away from the cross tube 12 in the direction of the applied force F. This is resisted, however, by the cross member 12, and the manifest consequence is that the force thus exerted on the spring clip tends to spread the legs thereof, but this produces an even tighter clasp of the legs of the clip 25 on the underside of the related arm 21, preventing to an even greater degree displacement of the tensioned arm 21 outward away from the cross member 12. In other words, a force tending to upset a roll itself results in the creation of conditions resisting this in proportion to the degree of the applied force. It may be further observed that the clips 25 also resist lateral swinging of the rolls R, that is, swinging motion in a left or right hand sense as viewed in FIG. 2.

The end arms 22 are four in number, two at each end of the member 12 and are secured in clips 25 in the manner of the arm 21. The clips 25 for the arms 22 are in adjacent relationship at each end of the cross member 12. The arms 22 are angled in the manner illustrated in FIG. 2 so as to diverge from one another outwardly at each end of the cross member 12, thereby to dispose the outer ends of each end pair of arms 22 beyond the ends of the member 12 in such positions that the downwardly bent anchor ends thereof (not shown, but identical to 21B) will locate the related two end rolls in surrounding or protective relation with respect to the base plates 16 and 17. This avoids the plates 16 and 17 being tripped over, and additionally results in a neat appearance.

The present invention, as will be realized from what has been described above, affords an effective way of safely displaying large, heavy rolls of linoleum or the like in an upright fashion. Any force tending to tip a roll over simply produces an even firmer anchor of the roll by virtue of this force being applied to the spring clip in such a manner as to spread the legs thereof, causing an even tighter clasp on the arm that anchors the roll. Hence, while I have illustrated and described a preferred embodiment of my invention, it is to be understood that this is capable of variation and modification, and I therefore do not wish to be limited to the precise details set forth, but desire to avail myself of such changes and alterations as fall within the purview of the following claims.

I claim:

1. In a display rack for upright rolls of linoleum or the like, a stand including a horizontal cross member supported at an elevation corresponding approximately to the height of the rolls, a U-shaped spring clip having the bight portion thereof supported on the cross member and the two legs thereof being disposed on opposite sides of the cross member, said legs each having an aperture there-

in substantially in registry one with another, a horizontal arm projected through the apertures and gripped by said legs, said arm at one end being adapted to be anchored to the upper portion of such a roll so that a force tending to tip the roll over applied tension to said arm, and said arm being joined to the leg of the clip which is on the near side of said roll.

5 2. In a display rack for upright rolls of linoleum or the like, a stand including a horizontal cross member supported at an elevation corresponding approximately to the height of the rolls, a plurality of U-shaped spring clips and each having the bight portion thereof saddled on the cross member with the two legs thereof disposed on opposite sides of the cross member, said legs each having an 10 aperture therein substantially in registry one with another, a plurality of horizontal arms, each of said arms projected through the apertures of one of said clips and related thereto so that the arms project from both sides of the cross member to anchor two rows of rolls on end respectively on opposite sides of the cross member, each of said arms at one end being adapted to be anchored to a related one of the rolls so that a force tending to tip a roll applies 15 tension to said arm, and each of said arms being connected to the leg of the related clip which is on the near side of the roll anchored thereby.

20 3. In a display rack for upright rolls of linoleum or the like, a stand including a horizontal cross member supported at an elevation corresponding approximately to the height of the rolls, a spring clip pivotally supported on the cross member and having two legs disposed on opposite sides of the cross member, said legs each having an aperture therein substantially in registry one with another, a horizontal arm projected through the apertures and the legs of the clip engaging said arm under spring 25 tension to retain the same, said arm at one end being adapted to be anchored on such a roll so that the force tending to tip the roll applies tension to said arm, and said arm being connected to the leg of the clip which is on the near side of said roll whereby when said arm is tensioned said legs are spread farther to apply more spring 30 tension to retain said arm.

40 4. In a display rack for upright rolls of linoleum or the like, a stand including a horizontal cross member at an elevation corresponding approximately to the height of the rolls, a spring clip supported on the cross member, said clip including two spring legs disposed on opposite sides of the cross member, said legs having aligned apertures therein, a horizontal arm supported in said apertures and thereby supported by said legs, said arm at one end being 45 adapted to be anchored on such a roll so that the force tending to tip the roll applies tension to said arm tending to displace the arm relative to said spring legs, and said arm being connected to the leg of the clip which is on the near side of said roll whereby said displacing force tends to spread said legs and to move the edges of said apertures 50 into tighter contact with said arm thereby resisting said displacing force.
